US00D461610S

(12) United States Design Patent **(10) Patent No.:** **US D461,610 S**
Perelli **(45) Date of Patent:** **** Aug. 13, 2002**

(54) DUST PAN WITH WEAR REDUCING MEMBERS

(75) Inventor: **Thomas Perelli, Winchester, VA (US)**

(73) Assignee: **Rubbermaid Commercial Products LLC, Winchester, VA (US)**

(**) Term: **14 Years**

(21) Appl. No.: **29/130,586**

(22) Filed: **Oct. 5, 2000**

(51) LOC (7) Cl. **07-05**

(52) U.S. Cl. **D32/74**

(58) Field of Search **D32/74; 15/257.4, 15/257.8, 257.9, 257.1**

(57) CLAIM

The ornamental design for a dust pan with wear reducing members, as shown and described.

DESCRIPTION

FIG. 1 is a top side perspective view of the dust pan with wear reducing members with a cover in a closed position; FIG. 2 is a bottom side perspective view of the dust pan with wear reducing members with a cover in a closed position; FIG. 3 is a frontal perspective view of the dust pan with wear reducing members with a cover in an open position; FIG. 4 is a rearward perspective view of the dust pan with wear reducing members with a cover in an open position; FIG. 5 is a left side view of the base with a cover in an open position, the right side view is the mirror image; FIG. 6 is a front side view of the base with a cover in an open position; FIG. 7 is a top side view of the base with a cover in an open position; FIG. 8 is a back side view of the base with a cover in an open position; and, FIG. 9 is a bottom side view of the base with a cover in an open position.

The broken lines in the drawings are for illustrative purposes only and form no part of the claimed design.

The handle is partially shown for convenience of illustration.
